UNITED STATES PATENT OFFICE.

HASWELL A. SWASEY, OF NEW ORLEANS, LOUISIANA.

MOP.

Application filed September 9, 1922. Serial No. 587,142.

To all whom it may concern:

Be it known that I, HASWELL A. SWASEY, a citizen of the United States, residing at New Orleans, in the parish of Orleans and 5 State of Louisiana, have invented a new and useful Mop, of which the following is a specification.

This invention relates to brushing and scrubbing, and more particularly to floor 10 mops of the type known as dry hand mops.

The object of the invention is to provide a mop of this character so constructed that it may be wrung dry without wetting the hands, which is self wringing and self 15 rinsing and which may be used as a scrub mop in addition to performing the functions of the ordinary mop.

Another object is to provide a mop, the head or mopping element of which may be 20 readily renewed by an inexperienced person, and which is constructed to preclude its losing its shape or symmetry, and which when in operation presents a solid mopping surface thereby adapting it for use in 25 scrubbing as well as mopping.

Another object is to provide a mop of this character in which the head is so mounted on the frame as to prevent all 30 possibility of scratching the floor or furniture.

Another object is to provide a mop of this character composed of few parts and including a frame having a cylindrical hand 35 grip molded integral therewith and which is strong and free of any attachments such as would be likely to get out of order.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 45 within the scope of what is claimed without departing from the spirit of the invention.

In the accompanying drawings:

Figure 1 represents a side elevation of a 50 mop constructed in accordance with this invention with parts of the handle broken out for convenience in illustration, and the mopping member stretched prior to wringing;

Figure 2 is a bottom plan view;

Fig. 3 is a transverse section taken on the 55 line 3—3 of Fig. 1;

Fig. 4 is a section on line 4—4 of Fig. 1;

Fig. 5 is a side elevation of the connector;

Fig. 6 is a detail section of the mop;

Fig. 7 is a side elevation of the mop in 60 position ready for use as a scrubber;

Fig. 8 is a similar view with the mop thrums shown twisted for wringing; and

Fig. 9 is a section taken on line 9—9 of 65 Fig. 7.

In the embodiment illustrated, the mop constituting this invention comprises a mop head holder or frame 1 slidably mounted on a handle 10 and connected therewith by a mopping element or head 20, the head 70 being secured to the handle by a connector in the form of a clamp 15.

The frame 1 which constitutes a part of the invention is constructed of rust proof metal in elongated bail-shaped form with 75 the side members 2 and 3 diverging toward their outer ends, and connected by a cross bar 4. This cross bar 4 has a plurality of longitudinally spaced apertures 5 for the connection of the head 20 therewith in a 80 manner presently to be described.

The inner ends of the side bars 2 and 3 of frame 1 are connected by a cross bar 6 which is widened as shown clearly in Fig. 3 to form a hand guard to prevent the contact of the user's hand with the mop head 20, and against water during the wringing operation of the mop. Extending centrally outward from the cross bar 6 is a handle encircling cylindrical hand grip 7, the outer 90 face of which is knurled or serrated as shown at 8 to afford a firm grip during the wringing operation. This cylindrical hand grip 7 is provided at its outer end with a bead 9 which prevents the hand of the user 95 from slipping off the member 7.

The handle 10 may be of any desired length and preferably constructed of hard wood, with a portion thereof peripherally corrugated to provide a hand grip 11 which 100 is positioned at any suitable point convenient for the user.

The connector 15 which is designed for securing the head or mopping element to the lower end of the handle 10 may be of 105 any suitable or desired construction, but is preferably made in the form of two semi-circular jaws 16 and 17 of rust proof metal;

and which are hingedly connected at their meeting ends by a pin 18 which passes transversely through the lower end of the handle 10 and is detachably secured in adjusted position by a cotter pin 19, or other suitable fastener.

The meeting ends of the jaws 16 and 17 are apertured and arranged inlapping relation with their meeting faces 16^a and 17^a cut away at their lapping points as is shown clearly in Fig. 5.

The head 20 is constructed of a single thread or strand of cotton fiber which is folded back and forth to form two layers 21 and 22 each of which is composed of two of the fiber strands or thrums 23. These superposed layers 21 and 22 are stitched together transversely at longitudinally spaced intervals as shown at 24 and at the central 20 or frame attaching portion thereof has a double row of stitching 25 the two rows being spaced apart a distance corresponding substantially to the width of the cross bar 4 of the frame 1 to which it is to be connected. In the mounting or connection of the head 20 with the frame 1, the portion of the head equipped with the double row of stitching 25 is arranged over the outer face of the crossbar 4 of frame 1 and is 25 secured thereto by a row of stitching 26 which passes through the apertures 5 in the cross bar 4, and through the head between the lines of stitching forming the double row 25, as is shown clearly in Fig. 2. 30

35 The folded ends of the head 20 are connected with the clamp 15 by disconnecting the members 16 and 17 thereof which is accomplished by removing the pin 18. These members 16 and 17 are then passed through the loops of strands at the ends of the head 20 and said members connected with the pin 18 which is secured by means of a cotter pin 19 or otherwise.

The head 20 is made of a width slightly 45 greater than the length of the cross bar 4 so that when said head is secured to said cross bar, the side edges thereof will project over the corners of the frame 1 formed by the union of the side bars 2 and 3 with 50 the cross bar 4, and thereby provide a buffer which will protect the floor and furniture against scratching by the frame 1.

The mop head 20, when connected in the manner above described and the handle moved to its extreme rearward limit in frame 1 will assume the position shown in Fig. 1 presenting a fan like appearance which is the position of the mop preparatory to wringing.

60 The arrangement of the head 20 over the cross bar 4 in the manner shown in Fig. 7 presents a solid surface engaging scrubbing member adapting the mop to be used either as a scrubber or as a mop.

65 When it is desired to wring out the mop

head 20, the metal handle grip 7 is grasped by the left hand while the corrugated hand grip of the handle 10 is grasped by the right hand, and the handle moved rearward to the position shown in Fig. 8. The frame 70 which is then rotated operates to wind one member of head 20 on the other as shown in Fig. 8 performing a wringing operation similar to that which would be accomplished by grasping the mop by the hands and 75 wringing it. This wringing of the mop, it will be observed, will be accomplished without the hands coming in contact with the head or with the water so that it is properly termed a dry hand mop.

80 It is of course understood that the members of the mop are unwound by reversing the operation above described.

When it is desired to rinse out the mop head 20, it is placed in a bucket of soapy 85 water and the handle 10 reciprocated in the cylindrical hand grip 7 performing a churning motion whereby the head will be thoroughly cleansed without necessitating the user stooping over or wetting her hands.

90 The frame 1 has the end and side members thereof constructed rectangular in cross section arranged edgewise so that maximum strength will be provided with a minimum amount of metal.

95 It will be seen from an inspection of the drawings and reference to the above description that the mop constituting this invention is composed of four parts only to wit: the solid cast metal frame 1, the hard 100 wood handle 10, the fiber mop head 20 sewed to the frame 1 in such manner as to present its entire surface or bulk to the floor in a symmetrical manner, and the connector 105 which secures the ends of the head 20 directly to the handle.

The method of stitching the yarn or fiber strands transversely was arrived at by much 110 experiment and the effect obtained thereby is to give the mop while in operation a compact fan like appearance as shown in Fig. 7 holding it substantially in that shape and presenting to the floor or other surface an even flat mop with which to scrub or 115 mop, the four folds of the yarn lying so closely together that all are effective. This is accomplished by moving the handle to its extreme forward limit as shown in Fig. 7.

120 The securing of the mop head to the cross bar 4 by means of the heavy thread 26 passed through the holes 5 in the cross bar 4 and between the rows of stitching 25 provides an absolutely firm and secure connection between the head and the frame rendering it impossible for the head to pull or 125 get out of shape and adapting the head 20 to be readily removed and a new one substituted, the connector 15 which connects the head with the handle being also easily disconnected for this purpose. It will thus 130

be seen that the handle and frame will last indefinitely and that the mopping element may be cheaply and easily renewed so that the first cost of the mop is practically the only cost.

5 I claim:

A mop holder comprising a substantially elongated bail-shaped member with the side members thereof made of metal substantially rectangular in cross section, and flaring toward their outer ends, cross bars rigidly connecting said ends, the cross bar at the inner end of the side bars having a widened

portion to form a hand guard and an upwardly extending cylindrical sleeve to receive a handle, the cross bar at the wide end of the holder provided with apertures for the attachment thereto of a mop head.

15 In testimony that I claim the foregoing as my own, I have hereto affixed my signature in the presence of two witnesses.

HASWELL A. SWASEY.
